UNITED STATES PATENT OFFICE.

WILLIAM K. LIGGETT, OF COLUMBUS, OHIO, ASSIGNOR, BY MESNE ASSIGNMENTS, TO THE
JEFFREY MANUFACTURING COMPANY, A CORPORATION OF OHIO.

CONVEYER.

No. 902,421.

Specification of Letters Patent.

Patented Oct. 27, 1908.

Application filed January 30, 1906. Serial No. 298,658.

To all whom it may concern:

Be it known that I, WILLIAM K. LIGGETT, a citizen of the United States, residing at Columbus, in the county of Franklin and State of Ohio, have invented certain new and useful Improvements in Conveyers, of which the following is a specification, reference being had therein to the accompanying drawing.

10 This invention relates to improvements in conveying apparatus, they being particularly well adapted for use in constructing portable conveyers of the sort employed for the loading of closed cars or box cars.

15 Figure 1 is a plan view of a mechanism embodying my improvements. Fig. 2 is a view partly in longitudinal vertical section and partly in side elevation of the mechanism, a car being shown in cross section.

20 Fig. 3 is a view showing the conveyer proper in side elevation, the framework and other parts being shown in vertical transverse section and the car being shown in longitudinal section, the conveyer being extended toward

25 the left. Fig. 4 is a perspective showing conventionally the manner of supporting and guiding a conveyer belt or apron. Fig. 5 is a cross section of the belts constituting an apron and showing the roller or rollers

30 which support them in side view. Fig. 6 is a plan view of the shafting and gearing for moving vertically the inner ends of the truss systems or lazy tongs systems.

In the drawings, A indicates a car track 35 and B a car or vehicle thereon. By the side of the track there is constructed a support or platform C of suitable character. Above this there is a vertically adjustable frame or platform for directly supporting the movable structure which carries the conveying apparatus and which is made vertically adjustable in order to have it adapted for use with cars having floors at different elevations from the track.

40 The framework of the portable structure comprises a base part or horizontally disposed part and a vertical or upwardly extended part. The former has longitudinal beams 1, 1, and cross bars or girts 1^a, 1^b, 1^c.

45 The upwardly extending part of the frame comprises standards 2, 3, the connecting bars or plates 3^a joining these, the inclined bars or braces 67, and the forwardly projecting frame bars 67^a at the top and 67^b at the bottom. Upon this framework are supported

two systems of truss bars or levers, those of each system being arranged and connected together on the plan of a lazy tongs. Upon each side of the conveyer there is a series of lever bars 4, 6, 8, 10 arranged parallel to each other, and also a series of bars 5, 7, 9, and 11, parallel to each other, but inclined to and crossing the bars 4, 6, 8, 10 respectively. One of the inner bars 4 is pivoted to one of the uprights or standards at 12. 65 Its companion bar 5 is pivoted to a vertically adjustable nut 13. The latter is fitted in a way in a guide 14 which permits it to slide vertically.

Outer bars 11 of the truss system support 70 the extreme roller 15 for the belt. At each of the top joints of the lazy tongs bars there is a belt roller 16 carried by a crank bar or arm 16^a secured to the hinge devices in such way that they shall maintain a substantially 75 constant angle relative to vertical planes, the belt 17 in consequence being supported thereon uniformly irrespective of the position of the lazy tongs or truss rods.

A single belt may be used, or a series of 80 narrow belts can be used, and so supported and related to each other as to give a wide supporting and transporting device for the material placed upon them.

In the drawings three belts are shown, 17^a, 85 17^b, 17^c. The two extreme rollers 15, 15 are formed in three sections, as at 15^a, 15^b, 15^c. These sections gradually increase in diameter and may be tapered somewhat. The belt at 17^b overlaps that at 17^a and the one 90 at 17^c overlaps that indicated by 17^b. These belts all pass around the same driving pulley 20, they overlapping each other thereon. For the right hand side of the mechanism there are three vertical rollers 19^a, 19^b, 19^c, 95 one for guiding each of the aforesaid belts; and for the other side of the mechanism there are three similar vertical rollers. These are mounted in supporting pieces 75 and are so arranged with relation to the 100 driving pulley 20 as to cause the superposing of the belts one upon the other, as above described. And to compel them to hug and press tightly against the greater part of the periphery of the guide pulley I use guide 105 pulleys 21, 21 mounted in the same framework which sustains the drive pulley 20. This pulley is rotated by the main line shaft 22 which is driven from the motor 23 by the gears 24, 25. The drive pulley 20 is 110

mounted in a frame or housing having the upper and lower parts 26 which furnish bearings for the vertical shaft 29 carrying at its lower end the bevel wheel 28 with 5 which meshes the pinion 27 on the main shaft 22, the latter having a featherway or slot 32 which permits the bevel gearing 27 to move from one position to another along the shaft without losing its driving connection. 30 is the bearing sleeve which supports the bevel 27 and surrounds the shaft. The drive pulley 20 and its carrying frame are supported by brackets or lugs 26^a which are fitted to bars or plates 26^b on the main 10 frame and which can move more or less in relation to that frame so as to permit the taking up of the slack and the regulation of the tension of the belts. The tension is regulated and maintained by means of a 15 weight 33 adapted to move down or up in a well 34, this weight being sustained by a cable 35 which is secured to the rear end of the frame 26 of the drive pulley 20 and is fitted to and bears against the idler sheaves 20 or pulleys 36, 38, and 39 mounted stationarily on the platform, the cable also passing around the pulley 37 secured to the weight and having its end fastened at 40 to the rear axle of the truck wheels. The truck wheels 25 are indicated by 41 at the rear and 42 at the front. The portable structure is all supported upon these wheels, which in turn rest upon the rails or bars 43 of the platform above referred to.

30 35 44, 45 are gear wheels provided with a hand crank device 46 by which they can be rotated, and the gear 44 being secured to the front axle of the truck the whole mechanism can be moved longitudinally as desired.

40 At 47 there is a jack screw which supports the front end of the adjustable platform or frame section 43, the rear end being supported in such way as to permit the front end to be raised or lowered.

45 The sliding nut blocks 13, 13 hereinbefore referred to are moved in vertical directions by means of the screw shafts 50, 51. For each set or system of lazy tongs there are two of these nuts and shafts, one at each 50 side of the belt. The shafts are simultaneously rotated by means of a cross-shaft 52, which is provided at each end with a bevel pinion 53 that meshes with a bevel wheel 54 secured to one of the vertical screw shafts.

55 Power is imparted at will to either of the shafts 52 from a countershaft 62 which lies under and transversely to the main power shaft 22. The power shaft 22 drives the countershaft through the spiral gearing 60, 61. On the ends of the countershaft 62 there are friction pinions 63. At the center of each of the shafts 52 there is a sleeve 55 provided with two friction wheels 55^a 55^b and with a groove 57 for a shifting device.

60 65 Each sleeve is feathered to its shaft 52 so

that it can be moved in one direction or the other so as to bring one or the other of the wheels 55^a or 55^b into frictional contact with the pinion 63.

58 is a shifting lever connected to the sleeve 55 and also connected to the hand lever 59 by the rod 58^a. There is one of these trains of sleeve shifting devices for each of the truss systems. The operator can whenever desired cause one of the sets of sliding nuts 13 to move downward and this in turn will cause the drawing in or contracting of the truss system on that side which is controlled by said nuts, and he can simultaneously or at a time theretofore or thereafter bring into action the other screw shafts and cause their sliding nuts 13 to move upward, which will in turn compel the lazy tongs system or truss bars with which they are connected to elongate.

85 The material to be loaded is fed through a spout 74 upon a vibrating feeder 65. The latter is provided with an inclined end board 66, a bottom 68 and side walls 77. Its inner end is open and extends over the conveyer belt. This feeder is mounted upon the elevated frame 67, 67^a, being supported by wheels 69, which run upon the horizontally-arranged bars 67^a. The table is reciprocated through gearing connected with the main power shaft 22. The end of the latter which is the most distant from the motor is provided with a bevel pinion 76 that meshes with and drives a bevel wheel 73 supported upon a vertically-disposed shaft 72 mounted in suitable bearings. At the upper end of this shaft there is a crank 71 which is connected, by the link 70, with a pin 78 extending downward from the bottom of the reciprocating feeder. The edge of the upper connecting bar or plate 3^a that is opposite the open end of the reciprocating feeder is carried upward, as indicated in Figs. 2 and 3, in order to prevent the material being fed entirely across the belt.

100 It will be understood that the belt or endless conveyer rests upon the upper connecting plate 3^a, which thus forms a firm support therefor at the place where the material is fed upon it.

105 When not in use the apparatus is moved back and rests upon the stationary framework supported upon the platform C. When a car is to be loaded it is moved into place opposite the platform and the portable frame carrying the loading apparatus is, through the hand mechanism 44, 45, 46, etc., moved outward so as to extend into the car, as indicated in Fig. 2. The motor being started drives the main pulley 20, around which the belts pass, and thus drives the belt conveyer. By means of the shifting mechanism controlled by the hand lever 59, the conveyer is extended in one direction or the other as desired, so that the parts assume a 110

position like that indicated in Fig. 1 or Fig. 3, when the material may be delivered to the belt by means of the reciprocating feeder device 65. As the material is piled up and 5 fills that end of the car toward which the conveyer is projected, the truss or lazy tong frame is gradually retracted until finally it assumes the position indicated at the right-hand side of Fig. 3. When one end of the 10 car has been filled the conveyer truss frame on the other side is extended and the opposite end of the car is filled, as may be understood without further detailed explanation.

It will be understood that the counter-balancing weight 33 operates both to take 15 up the slack and maintain tension upon the belt or belts at all times, whatever be the positions to which the truss frames may be adjusted, and insures the belts being held 20 under tension when the loader is not in use and is moved back out of the car and over the platform C.

What I claim is:

1. In a conveying apparatus, the combination of a frame, suitable rollers or pulleys, and a plurality of relatively movable carrying belts or aprons on the said rollers or pulleys arranged to have the material-carrying portions thereof situated side by 25 side and with the edge of each belt nearest one side of said frame overlapping the adjacent edge of the adjoining belt, substantially as set forth.

2. In a conveying apparatus, the combination of a frame, suitable rollers or pulleys, and a plurality of relatively movable carrying aprons or belts on said pulleys or rollers, and arranged to have said carrying belts situated side by side and their driving 30 parts overlapping one upon another, in series upon a common driving pulley substantially as set forth.

3. In a conveying apparatus, the combination of a frame, suitable supporting rollers or pulleys turned on horizontally disposed axes, a driving pulley or roller turning on an axis that is not horizontal, a carrying belt supported upon the horizontally disposed rollers or pulleys and passing 45 around the driving pulley, and guides between the driving pulley and the said horizontal rollers or pulleys, substantially as set forth.

4. In a conveying apparatus, the combination of a frame, an endless conveying belt or apron, an extensible frame for the latter, rollers mounted in the said extensible frame turned on horizontal axes and arranged to support the conveying portion of the belt, 50 a driving pulley in the supporting frame turning on an axis that is not horizontal and about which pulley the carrying belt passes, and guides for the belt between the driving pulley and the said horizontal rollers, substantially as set forth.

5. In a conveying apparatus, the combination of a frame, suitable rollers or pulleys turning on horizontal axes, a driving roller or pulley turning on an axis that is not horizontal, a plurality of carrying belts or 55 aprons overlapping upon the said driving roller or pulley and lying side by side on the horizontal pulleys, and guides between the driving pulley and the said horizontal rollers or pulleys, substantially as set forth. 75

6. In a conveying apparatus, the combination of a frame, suitable horizontal belt-supporting pulleys or rollers, a driving pulley or roller, a plurality of carrying belts or aprons having their carrying portions arranged side by side, and having their driving portions arranged to overlie one upon another, and a series of approximately vertical guide pulleys or rollers, each engaging 80 by one of the said belts or aprons and interposed between the driving pulley and the said horizontal pulley or rollers, substantially as set forth. 85

7. In a conveying apparatus, the combination of a frame, the pulleys or rollers, 90 having a progressive series of sections of different diameters, and a plurality of relatively movable belts or aprons having their carrying portions side by side and each fitted to one of the said sections on each of the 95 rail rollers or pulleys, substantially as set forth.

8. In a conveying apparatus, the combination of a frame, a belt guide system having at one end a pulley or belt support 100 formed in parts of progressively varying diameters, and having at the other end of the system a belt support formed in sections of progressively varying diameters, and more than two relatively movable endless carriers 105 or aprons each arranged side by side to travel around one of the parts on each of the said belt supports, and said belts having overlapping edges, substantially as set forth. 110

9. In a conveying apparatus, the combination of a frame, a plurality of carrying belts, supporting rollers for the belts arranged to turn upon approximately horizontal axes, a driving pulley for the belts mounted to turn upon an approximately 115 vertical axis, and means for maintaining the belts side by side while supported upon the horizontal rollers and for maintaining them overlying one on the other while passing around the driving pulley, substantially as set forth.

10. In a conveying apparatus, the combination of a main frame, an endless carrier or belt, an extensible frame for the carrier or belt, a driving device on the main frame 120 for the belt, and means for moving the belt-driving device to cause it to maintain tension upon the belt and the engagement thereof with the driving device, substantially as set forth. 125

11. In a conveying apparatus, the combination of a main frame, an endless carrier or belt, a longitudinally extensible frame for the carrier or belt, means for extending and contracting the carrier frame, a driving device for the belt or carrier, mounted on the main frame, and bodily movable relative to the extensible carrier frame, and an automatic tension device for bodily moving the carrier driving device to maintain tension upon the belt and the engagement thereof with the driving device under the different positions to which the extensible frame may be adjusted, substantially as set forth.
12. In a conveying apparatus, the combination of a main frame, a power shaft mounted in the main frame longitudinally thereof, an endless carrying belt, an extensible frame in which the belt is supported, a driving device for the belt connected with the power shaft and movable lengthwise thereof and relative to the said extensible frame, and an automatic tension device connected with the driving device and arranged to move it along the power shaft to maintain the proper tension upon the belt as the extensible frame is adjusted, substantially as set forth.
13. In a conveying apparatus, the combination of a stationary frame, a main supporting frame longitudinally adjustable upon the supporting frame, a laterally extensible frame carried by the said main frame, an endless belt mounted in the said extensible frame, means for driving the belt mounted in the main frame, and a tension device for the belt supported by the said stationary frame, substantially as set forth.
14. In a conveying apparatus, the combination of a main frame, an endless carrier or belt, an extensible frame therefor mounted in the main frame, means for adjusting the said extensible frame to cause it to project more or less from the main frame, a power shaft mounted in the main frame, a driving pulley around which the belt or carrier passes, a movable frame in which the driving pulley is mounted, gearing between the driving pulley and the power shaft, the said gearing and the frame for the driving pulley being together movable lengthwise of the power shaft, a weight, and a flexible connection between the weight and the frame of the driving pulley arranged to cause the weight to move the driving pulley and maintain proper tension upon the carrier or belt, substantially as set forth.
15. In a conveying apparatus, the combination of a stationary support, a longitudinally movable main frame on the said support, a carrier belt frame carried by the main

frame and laterally extensible relative thereto, means for extending and contracting the said carrier belt frame, an endless belt mounted in the said extensible frame, a driving pulley about which the carrier belt passes mounted in the main frame, and tension devices mounted on a stationary support arranged to maintain the carrier belt under proper tension as the main frame is longitudinally adjusted upon its stationary support and also as the extensible frame is adjusted relative to the main frame, substantially as set forth.

16. In a conveying apparatus, the combination of a stationary support, having the rails or bars 43, a main frame longitudinally adjustable upon the said rails or bars, a transversely arranged extensible belt frame carried by the main frame, means for extending and contracting the extensible frame, a belt or endless carrier mounted in the said extensible frame, a driving pulley 20 for the belt, a longitudinal power shaft 22, gearing between the power shaft and the belt pulley 20, a frame 26 in which the belt pulley is mounted, said frame 26 and the gearing being together movable lengthwise of the power shaft 22, a vertically movable weight 33, a rope 35 connected at one end with the frame 26 and at the other end to some portion of the movable frame, and pulleys for guiding the rope and supporting the weight 33 therefrom, substantially as set forth.

17. In a conveying apparatus, the combination of a longitudinally movable main frame, a pair of extensible belt-carrying frames supported by the main frame, each comprising a lazy tong system of bars, each system being arranged to be lengthened or shortened independently of the other, an endless belt supported in the said extensible frames, a driving device for the said belt, a power shaft 22, gearing between the power shaft and the driving pulley, independent means connected with each lazy tong system of bars for adjusting the extensible frames, a shaft 62 driven by the main power shaft, shafts 52 for operating the adjusting devices for the respective systems of bars, and adjustable, independent, clutch devices for connecting the shaft 62 with the shafts 52, respectively and at will, substantially as set forth.

In testimony whereof I affix my signature, in presence of two witnesses.
